UNITED STATES PATENT OFFICE

2,373,317

ROOF COVERING

Thomas A. Lawson, San Francisco, Calif.

Application May 2, 1942, Serial No. 441,497

2 Claims. (Cl. 108—6.5)

This invention relates to improvements in Roof Coverings and more particularly to composite fireproof shields for roof coverings.

Among the objects of the invention is the provision of a stratified shield composed of non-combustible granular minerals, adapted to be easily applied to conventional flat roofs.

Another object is the protection of the underlying roof with a friable shield that may be easily removed to permit access to any portion of the roof for repairing.

Another object is the utilization of easily obtainable materials in the composition of the shield to facilitate its application to the roof without specialized skill and at a reasonable price.

A further object is the accomplishment of the above objects with minimal weight per square foot of roof area.

Other objects and advantages will appear as the description progresses.

In the specification and the accompanying drawing the invention is disclosed in its preferred form. But it is to be understood that it is not limited to this form because it may be embodied in modifications within the spirit of the invention as defined in the claims following the description.

In the one sheet of drawings:

Fig. 1 is a fragmentary detail of a portion of a roof adjacent the side wall, having this invention applied thereto and shown in vertical section.

Fig. 2 is a diagrammatic representation of the relative positions of the various layers of material forming the fireproof shield applied to a conventional gravel roof, shown in dotted construction in vertical section.

In detail the construction illustrated in the drawing, referring first to Fig. 1, comprises the usual roof sheathing 1, resting on the rafters such as 2, supported by the wall studding 3. Flat roofs have the concealing coping 4 attached to the upper portions of the surrounding wall.

The conventional roof covering consists of the heavy fiber sheets 5 impregnated with water proofing, such as fluid asphalt, tar or the like. The edge of the first side sheet is folded up the side wall and attached to the coping board 4. The edge of the next sheet 5 is overlapped to form a seam at 5' that is nailed to the sheathing.

The top surface of the fiber sheets is then given a heavy coating of tar 6 brushed on in a manner to seal all the seams 5' and the upper edges of the sheets where they join the coping 4. While 55

the tar coating 6 is still fluid or "tacky" a layer of coarse and fine gravel 7 is spread evenly over the treated area. The gravel adhering to the coating 6 tends to anchor all the gravel against displacement by passing winds. The above describes a conventional flat gravel roof, having just enough inclination to provide drainage. There are various modifications of the above, such as prefabricated sheets having a top coating of fine slate aggregate instead of the pebble gravel 7, to which the present invention is equally applicable.

The heat from a glowing cinder or firebrand falling upon such a roof will release volatile gases from the tarr coating 6, feeding the flames until the fabric sheets 5 are ignited and the fire reaches the underlying sheathing 1.

The present invention consists of the composition and the method of applying a composite fireproof shield for any conventional form of flat roofing. The first step in the method is to distribute evenly over the surface of the gravel layer 7, a mat of asbestos fiber, rock wool or similar non-inflammable fibrous material. This fluffy layer is then tamped or patted down until it penetrates into the interstices in the gravel layer 7, beneath. A thin layer 9 of Portland cement or the like, is then sprinkled evenly over the mat 8 and sprayed lightly with water to form a thin skin of neat cement on the surface which gradually seeps into the fibers of the mat, but not enough to destroy the friability of the mat when the cement sets, but just enough to integrate the fibers to overcome the natural fluffiness. The layer of gravel or fine aggregate 10 is then evenly distributed over the top of the mat 8. A layer of Portland cement is then evenly distributed over the surface of the top gravel layer 10 and lightly sprayed with water, just enough to carry the pulverized cement down into the interstices in the gravel layer 10, and leave a cementitious glaze on its top surface.

The fibrous mat 8 need not be over $\frac{3}{8}$ to $\frac{1}{2}$ an inch thick. It is mechanically keyed to the gravel layer 7, but it does not adhere thereto, because of the poor adhesive qualities of Portland cement. This is desirable because it enables the easy removal of any portion of the fireproof shield 8—9—10 to expose the roofing 7—6—5 for repairing.

The fireproofing shield 8—9—10 is not intended to contribute to the waterproofing of the roofing beneath, except to an incidental extent. It has the advantage of thermal insulation, preventing

the loss of heat from beneath the roof, and against the penetration of sun heat from above.

Where the coping such as 4, is inflammable it is good practice to cover it with metal or asbestos sheeting such as 11, having its lower edge 12, folded outward beneath the mat 8. Such sheeting should be continued upward and over the top of the coping and secured by tacking or adhesion.

The porous mat 8 formed in the manner described, is superior to prefabricated sheets of asbestos or other non-inflammable material, because it is not subject to lifting by winds blowing across it. A more dense layer will tend to lift off the roof surface due to suction and be torn or displaced.

If preferred the fiber forming the mat 8 can be premoistened with water and spread over the roof like plaster. This is advantageous while working in windy weather.

Having thus described this invention what is 20

claimed and desired to secure by Letters Patent is:

- 5 1. The method of fireproofing a roof having a conventional covering consisting of superposing a continuous non-adhesive mat of fibrous non-inflammable material on said covering; applying a coating of Portland cement to the top surface of said mat; superposing a layer of loose gravel on top of said mat; applying a coating of dry 10 Portland cement on top of the gravel on said mat; and then moistening said structure with water.
- 15 2. In combination with a roof having conventional gravel roof covering; a continuous shield composed of noninflammable fibrous material impregnated with Portland cement to form a nonadhesive friable mat overlying said covering; a layer of Portland cement applied to said mat; and a top layer of gravel embedded in said layer of cement.

THOMAS A. LAWSON.
